TRAMMING LOCOMOTIVE

Glenn E. Edmunds, Columbus, Ohio, assignor to The Jeffrey Manufacturing Company, a corporation of Ohio

Application February 24, 1953, Serial No. 338,284

1 Claim. (Cl. 105—50)

This invention relates to tramming locomotives and an object thereof is to provide an improved locomotive of this type that includes improved operator's platform and drawbar structure that may be raised from a generally horizontal position to an upright position to reduce the overall length of the locomotive.

Another object of the invention is to provide an improved tramming locomotive that includes an operator's platform that may be swung from a generally horizontal position to a generally upright position to reduce the overall length of the locomotive and to provide in such locomotive improved means for pivotally attaching the platform to the locomotive and for securing the platform in its generally horizontal position in a manner whereby the operator's platform, in effect, becomes a rigid part of the main frame of the locomotive.

Still another object of the invention is to provide an improved tramming locomotive that includes an operator's platform which may be swung from a generally horizontal position to a generally upright position to reduce the overall length of the locomotive wherein the platform is pivoted to the locomotive to swing about an axis extending transversely of the locomotive main frame and wherein the platform is secured in its generally horizontal position by separable or releasable means located at an elevation or a position different from that in which said axis lies.

Still another object of the invention is to provide a locomotive of the type set forth wherein a drawbar means adapted to transmit push and pull forces to and from the locomotive extends from the locomotive main frame across the operator's platform, is detachably secured to the locomotive main frame, and cooperates to retain the operator's platform rigidly in a generally horizontal position and wherein the operator's platform may brace the drawbar against lateral strains.

Other objects of the invention will appear hereinafter, the novel features and combinations being set forth in the appended claim.

In the accompanying drawings:

Fig. 1 is a view in perspective looking at the control end of a tramming locomotive embodying the invention, the locomotive having its swingable operator's platform and drawbar in a generally horizontal position;

Fig. 2 is a view similar to Fig. 1, but showing the operator's platform and drawbar in its generally upright position wherein the overall length of the locomotive is reduced; and

Fig. 3 is a side view of the locomotive seen in Figs. 1 and 2, the operator's platform and drawbar being shown in its generally horizontal position, with parts broken away; and the upright position to which said platform and drawbar may be swung being indicated in dot-dash lines.

Many underground mines, particularly in countries foreign to the United States, have numerous ore producing levels, but frequently ore is not produced at any one of these levels at such a rate as to justify the permane installation of a locomotive at each level to haul the ore, and under these conditions it has become a practice to employ one or more tramming locomotives that may

2

readily be placed at different levels in the mine by means of elevator cages or hoists operating in relatively small elevator or mine shafts.

The dimensions of these cages or hoists are frequently such that only small locomotives and mine cars can be placed upon them and in many mines the dimensions of the cages or hoists are such that the locomotives employed must be expandible and contractible whereby when expanded they may provide an operator's platform and drawbar means at one end and when contracted they can be placed upon the mine cage or hoist and be moved from one mine level to the other. Generally speaking, this invention relates to such tramming locomotives, but, of course, it could be applied to larger locomotives.

One problem met with in locomotives of this type is that of providing structure whereby the operator's platform and drawbar, when positioned to carry the locomotive operator and to pull or push cars, will be stable and become, in effect, a rigid part of the main frame of the locomotive, thus providing a rigid platform and drawbar that will not unnecessarily jounce and jar both the locomotive and its operator. This invention deals, in part, with this problem.

The tramming locomotive illustrated in the drawings 25 includes the invention and is of the type above described. This locomotive includes a main frame 10 that is supported upon four traction wheels 11 adapted to run over mine rails 12. The main frame 10 carries a battery 13 that may be removed from the locomotive and placed upon a charging rack. In mines where these locomotives are employed, it is customary to have at least two batteries 13 in order that one may be on the charging rack while the other is in use on the locomotive. The construction of the locomotive, per se, is not pertinent to this invention and therefore it suffices to say of it that it includes the usual electric driving motor, not shown, for the wheels, brake mechanism indicated generally at 14 for the wheels 11, and all other customary apparatus necessary to the proper functioning of the locomotive.

At one end of and supported by the locomotive main frame 10 the locomotive is provided with the usual control means such as a brake control wheel 15, an alarm bell 16, an electric rheostat or motor controller 17, gauges and the like, and a light 18. Below all of this apparatus and extending longitudinally from the end of the main frame 10 there is a box-like combination operator's platform and drawbar 19 that may occupy the position shown in Figs. 1 and 3 of the drawings when it is being employed to push or pull mine cars about a mine. This platform and drawbar carries an operator's seat 20 (see Fig. 1) that may be detached from the platform 19 when the latter is swung to the generally upright position shown in Fig. 2 of the drawings and in which position the overall length of the locomotive is reduced. As above mentioned the operator's platform 19 is a box-like member including spaced generally upright side walls 21, a bottom or floor 22 and an upright end member or wall 23. End wall 23 carries a coupler member 24 through which the locomotive may be connected to a mine car, for example.

The platform 19 is pivotally connected to the main frame 10 through two upwardly, angularly extending ear or lug portions 25 that are formed integral with or are parts of the spaced upright side walls 21 of platform 19 through two spaced pivot means in the form of machine bolts 26 (see Figs. 1 and 3) that may be threaded into appropriate openings formed in the main frame 10. These spaced pivot bolts 26 lie upon a common axis that extends transversely of the main frame 10 and above the floor 22 of platform 19 when said platform is in its generally horizontal position.

When the box-like platform 19 is in said generally

horizontal position its open end is closed by a wall that includes an upright plate 27 positioned at the center of locomotive main frame 10, and two curved wheel guards or boxes 28, one at each side of and attached to the side of said upright plate 27. The plate 27 and wheel guards 28 are integral parts of the main frame 10 and said plate 27 is notched at its bottom and substantially at its center as indicated at 29 in Fig. 2 of the drawings. The bottom of the plate 27 at each side of the notch 29 is bent at a right angle to provide extending portions 30 which are overlapped by tongues 30' on the bottom plate 22 and cooperate therewith to form parts of the bottom or floor of the platform 19.

At each side of the notch 29 there is attached to the plate 27, as by welding, an ear or lug 31 that extends from the plate 27 toward the platform 19. These ears or lugs 31 each include an opening, which openings are aligned to receive a pin 32 of a disconnectible or separable fastening means of which the ears or lugs 31 form parts. Loss of pin 32 is prevented by a chain welded at one end to the pin 32 and at the other end to the main frame 10.

The platform 19 includes a reinforcing member or drawbar element 33 that extends from the upright wall 23 of platform 19 substantially on the longitudinal center of platform 19 and between its side walls 21. This reinforcing or drawbar element 33 is L-shaped and has its short leg 34 welded to the wall 23 (see Fig. 3). Its long leg 35 extends adjacent the bottom or floor 22 and is preferably welded thereto. The end of leg 35 extends between the ears or lugs 31 and is provided with a transverse opening through which the pin 32 fits.

It will be seen that when the platform 19 is in its generally horizontal position and the separable or removable fastening means which includes the end of leg 35, the ears or lugs 31 and the pin 32, are assembled that the platform 19 is secured to main frame 10 and held in said generally horizontal position at three places, namely, at the pivot bolts 26 which lie on a common axis, and at the pin 32 of the separable fastening means. It will be seen that the pin 32 lies in a plane or is positioned below that plane in which the pivotal axis for the platform 19 lies and in a plane which is adjacent that plane in which the bottom or floor 22 lies when the platform is in its horizontal position. Because of this structure, pushing and pulling forces or strains are transmitted directly between the locomotive main frame 10 and the coupler means 24 through the drawbar element 33 and the body of the platform 19 braces the drawbar element 33 against lateral strains. It will also be seen that the drawbar or element 33 and the separable or disconnectible fastening means including the pin 32 cooperates with the pivot bolts 26 to secure the platform in its horizontal position and in such manner that the platform is rigidly connected to and in effect forms a rigid part of the main frame 10, and that towing strains transmitted through it and the drawbar element 33 cannot move the platform from its generally horizontal position.

When the locomotive is to be placed upon a mine cage such as previously described, the platform 19 may be swung to the upright position shown in Fig. 2 and indicated in dot-dash lines in Fig. 3 of the drawings. This may be accomplished merely by withdrawing the pin 32 from the separable fastening means that connects the bottom of the platform 19 and the drawbar element 33 to the main frame 10 and by swinging the platform 19 about the axis on which the pivot bolts 26 lies to its upright position in which it covers some of the controls of the locomotive including the rheostat or motor controller 17. The operator's seat is, of course, removed from the platform 19 before it is swung to its upright position. The platform 19 is retained in its upright position by the pivot bolts 26 and a pair of pins 36, one on each side of the locomotive, that are fitted through openings 37 in each ear or lug 25 of the platform 19 and extend into

the ends of transversely extending tube 38 that is welded to and forms an integral part of the main frame 10. Loss of pins 36 is prevented by chains 39 each welded at one end to one of the pins 36 and at the other end to one of the ears or lugs 25.

When said platform is in its upright position an operator may walk behind and control the locomotive. In order that this may be accomplished the floor 22 of platform 19 is cut away to provide an opening 40 through which the operator may gain access to the control lever 41 of the motor controller 17. All other pertinent controls on the locomotive as well as the headlight 18 are positioned so that they are below the bottom end of floor 22 when the platform is elevated and therefore the operator can walk behind and control the locomotive as he drives it upon a mine cage under its own power.

A door 42 is hinged to the floor 22 to close the opening 40 when the platform is in its generally horizontal position. The hinges 43 for door 42 are positioned so that gravity holds the door 42 open when the platform is elevated.

From the foregoing it will be seen that by this invention there is provided an improved trammimg locomotive including an operator's platform that is secured to the locomotive main frame to swing from a generally horizontal position to a generally upright position about a transverse axis and that the platform is retained or secured in its generally horizontal position by another fastening means that is in a plane or position different from that of the pivotal axis in which the platform lies. It will also be seen that the structure here described provides a locomotive wherein most of the drawbar strains are carried through the operator's platform by a drawbar element that is secured removably but directly to the locomotive main frame and that this drawbar element cooperates with the pivot means for the platform to retain the platform in its generally horizontal position and when so cooperating becomes in effect a rigid part of the main frame of the locomotive.

Obviously those skilled in the art may make various changes in the details and arrangement of parts without departing from the spirit and scope of the invention as defined by the claim hereto appended and applicant therefore wishes not to be restricted to the precise construction herein disclosed.

Having thus described and shown an embodiment of the invention, what it is desired to secure by Letters Patent of the United States is:

A locomotive including a main frame, a box-like means at one end of said main frame forming an operator's platform and a drawbar including a floor, opposite upright side means and an end member, a pair of axially aligned pivot means one pivotally attaching each of said upright side means at one end and above said floor to said locomotive main frame whereby said box-like means can be swung from a generally horizontal position to an upright position to decrease the overall length of said locomotive, means between said spaced side means extending along the floor of said platform between said end member and said locomotive main frame adapted to transmit pushing and pulling forces between said end member and said main frame, and disconnectible fastening means interconnecting said last named means and said main frame at a position below said aligned pivot means, said disconnectible means cooperating with said pivot means for securing said platform and drawbar to said main frame in said generally horizontal position.
